UNITED STATES PATENT OFFICE.

CARL W. JOHNSON, OF BROOKLYN, NEW YORK, ASSIGNOR TO AMERICAN MACHINE & FOUNDRY COMPANY, A CORPORATION OF NEW JERSEY.

CRAYON POINTING AND LABELING MACHINE.

Application filed April 7, 1926. Serial No. 100,365.

This invention relates to a crayon pointing and labeling machine designed and adapted to automatically sharpen or point an end of each crayon and apply to its body a paper label. The crayons operated on are soft, fragile, and of the type employed for marking lumber, black-boards, etc.

The main object of the invention is the production of a machine for effecting the result referred to at low installation and maintenance cost, and capable of pointing and labeling a large number of crayons per minute. With this and other objects not specifically mentioned in view, the invention consists in certain combinations and constructions which will be hereinafter fully described and then specifically set forth in the claims hereunto appended.

In the accompanying drawings, in which like characters of reference indicate the same or like parts, Fig. 1 is an end elevation of a machine constructed in accordance with the invention; Fig. 2 is a side elevation of the machine shown in Fig. 1, as viewed in the direction of the arrows in Fig. 1; Fig. 3 is a side elevation of the label magazine and label transferring device; Fig. 4 is an end elevation of the same; Fig. 5 is a vertical section through the crayon holding and forwarding turret; Fig. 6 is an end elevation of the turret; Fig. 7 is a horizontal section of the pointing device; Fig. 8 is a vertical section of the same; and Fig. 9 is an end elevation of the point cutting device.

In carrying the invention into effect, there is provided crayon pointing means for forming a point on one end of each crayon, ejecting means for discharging a pointed crayon from the pointing means, and means whereby crayons are successively presented to said other means. In the best constructions contemplated, there is further provided label applying means for applying a paper label to each crayon, either before or after said crayon is pointed, but preferably before; and label and crayon assembling means whereby the labels and crayons are brought together preparatory to completion of the label applying operation and commencement of the crayon pointing operation. These various means may be widely varied in construction within the scope of the claims, for the specific structure selected to illustrate the invention is but one of many

possible concrete embodiments of the same. The invention, therefore, is not to be restricted to the precise details of the structure shown and described.

Generally speaking, the specific machine shown consists of a hopper in which a supply of unfinished crayons are supported and from which they are successively delivered by the action of gravity, a magazine in which a supply of paper labels are supported and from which they are successively delivered by the action of a suction transferring device, crayon and label assembling devices which carry labels and crayons from the magazine and hopper respectively to an assembling point, a paste applying device operating to make the labels adhesive in transit, a rotating crayon holding turret to which the assembled labels and crayons are delivered, devices for folding the labels about the crayons in said turret, a device for forming a point on each crayon in said turret after a label has been applied thereto, and an ejecting device serving to deliver the completely labeled and pointed crayons to a table or other receiving device.

The turret is provided with a series of crayon holding chucks which successively move into crayon receiving position. The label transferring device, by means of its suction head, successively takes the labels from the magazine, moves them past the paste applying device, and delivers them into assembling position over the crayon holding chuck which is in position to receive a crayon and label for further treatment. At the same time, the crayon transferring device successively takes crayons from the hopper and delivers them into assembling position over the label positioned over the turret chuck. A plunger then moves label and crayon into said chuck where they are assembled with the mid-section of the label stuck to the crayon while the ends of the label are in upstanding position above the perimeter of the turret. Then a folding device moves into engagement with the rear upstanding end of the label and folds it down on the crayon to which it sticks. The turret is then rotated a step, and during this movement the leading end of the label is folded down on the crayon by means of a stationary brush adjacent the path of the crayon holding chuck. Then the crayon

pointing device comes into action and forms the point on one end of the crayon. The finished product is then ejected from the crayon holding means, ready for packaging.

5 Referring to Figs. 1 and 2, the machine is mounted on the frame 10 carrying an upright 11 on which is supported the crayon hopper 12 having the door 13. The lowest part of the hopper terminates at the upper 10 part of a chute 14 down which the crayons slide to the crayon transferring device.

The chute, to prevent accumulation of chips and dust, is made in the form of a crate, the top and bottom consisting of 15 two or more strips permanently fastened to the brackets 15 and 16. For accessibility, the front strip 17 is attached removably, being fastened to the brackets 15 and 16 by means of the slotted crossbars 18 which permit its being lifted off after opening the door 13 which locks it when closed. In order to insure an uninterrupted feed of crayons through the chute 14, an agitator 19, pivoted on the pin 20, is mounted on 25 the bottom of the hopper 12, the free arm 21 of the agitator being connected, through the rod 22, with the lever 23 which has an up and down motion.

The crayon transferring device, forming 30 a part of the assembling means, consists of the slide 24, movable back and forth in a guide 25 forming a part of the bracket 15, and being provided with a clamping bar 26 which holds the crayon against the end 35 of the slide 24 while being transferred. The bar 26 is attached to the forward ends of two horizontal rods 27 passing through the slide 24, their other ends being provided with springs 28 bearing against the slide 40 24, and pushing the bar 26 toward the latter. The rods 27 are spaced a sufficient distance apart to permit the crayons to pass lengthwise between them. The guide 25, on outboard brackets, carries the lugs 29 in 45 which are supported the adjustable stop screws 30 registering with the free ends of the clamp bar rods 27. The slide 24 has the lug 31 which, through the link 32, is connected with the lever 33 from which the 50 slide 24 receives its reciprocating movement. The free ends of the rods 27, near the end of the back stroke of the slide 24, when the crayon transfer approaches the delivery mouth of the chute 14, engage with, 55 and are held stationary by, the stop screws 30, so that, on further backward movement of the slide 24, the latter pulls away from the clamp bar 26, permitting a crayon to pass into the gap thus produced between them. The entering crayon proceeds into 60 this gap until it is in line with the slide 24 and rods 27, when it comes to rest on the supports 34 projecting from the guide 25. On the subsequent forward stroke of the 65 slide 24, the springs 28 are gradually re-

leased, and, when the ends of the rods 27 are out of engagement with the stop screws 30, draw the clamping bar 26 tight, thus holding the crayon which by this time has moved clear of the supports 34. While the 70 crayon transfer moves forward to bring the crayon into loading position or position for assembly with a label, the slide 24 closes up the chute 14 so that no crayons can pass out thereof until the slide has returned. 75

The label magazine 35, shown in detail in Figs. 3 and 4, is mounted on the slide 26 movable vertically in the upright 11, the slide 36 being connected, by the link 37, with the lever 38 mounted on the shaft 39 which is supported in bearing brackets 40 and carries the arm 41 actuated by the connecting rod 42. To the slide 36 is fastened the bracket 43 holding the adjustable end plates 44 of the magazine. The bottom of the magazine is partly covered by the plate 45, allowing the lowermost label to hang down at one end.

The label transfer consists of the carrier 46 having the guide bars 47 slidable on the track 48 supported on the upright 11. The carrier 46, on the portion of its upper surface opposite the label magazine, has suction holes 49 communicating, through the suction ports 50 of the carrier 46 and the hose connection 51 with the vacuum pump 52. At the center of the suction head, the carrier has a rectangular slot 53 so dimensioned that the crayon can pass through it on its way to the turret. The carrier has the lug 54 to which is pivoted the adjustable connecting rod 55 connected with the lever 56. In feeding the label, the carrier 46 is moved backward by the lever 56 until the suction head 49 registers with the magazine 35. Then, the slide 36 is moved downward until the free end of the lowermost label in the magazine touches the suction head which seizes and holds it fast, and, on the forward movement of the slide pulls it out of the 100 magazine.

The label is carried past the paste applying device, the head of which, carrying the paste applying roller 57, is raised at the proper time to allow the carrier to pass 105 below it. Having previously been in contact with the paste drum 58 revolving in the paste pot 59 adjustably mounted on the pedestal 60, the paste roller 57 applies a coating of paste to the upper surface of the 110 label. The paste drum 58 is mounted on the shaft 61 which carries the gear wheel 62 meshing with the gear 63 which is mounted on the shaft 64 supported by the bearing bracket 65 and carrying the sprocket 66 115 which is driven by the chain 67 from the sprocket 68 mounted on the shaft 69. The paste roller 57 is supported on links 70 which are mounted in the head 71 with sufficient clearance to permit the paste roller 120

to rest on the label before the links are stopped by the head. The head 71 is supported by the connecting rod 72 which receives up and down motion through the 5 roller 73 from the lever 74.

At the assembling or loading point, there is a plunger or ram 75 suspended by a link 76 from the end of the lever 23, and moving vertically in the guide 77. When the crayon 10 transfer and label carrier have arrived at the loading point, the lever 23 pushes down the plunger 75, thereby forcing the crayon out from between the transfer slide 24 and the clamp bar 26 down upon the label on 15 the carrier 46, and with the label through the slot 53 of the carrier into the receiving device or chuck of the turret. By its passage through the slot 53, the label is folded around the bottom and the two sides of 20 the crayon, leaving the ends of the label upstanding.

As the label carrier now moves back to receive the next label, the finger 78, attached at the forward end of the carrier by means 25 of the lug 79, sweeps over the crayon now held in the turret chuck and thereby folds the rear upstanding end down upon the crayon to which it sticks. The other or leading end of the label is folded down on 30 the crayon during subsequent forward rotation of the turret by the curved brush 80 mounted on the upright 11 adjacent the path of the turret chucks.

The turret, Figs. 5 and 6, whose body 81 is mounted on the shaft 82, holds the crayons in chucks one wall of which is formed by the turret body and the other by a bar 83 which is pressed against a crayon by a spring 84 supported in the bracket 85 attached to the turret body 81, the bar 83 being pivoted to the bracket 85. The crayon rests on the V-shaped surface of a bar 86 which is fastened across the ends of push rods 87 which move the bar outwardly to eject the 45 crayon at a later time. The rods 87 have springs 88 held by collars 89 against the turret body 81, so as to hold the bars 86 down at the bottom of the chucks when the turret is moving and the rods are idle. The 50 turret shaft 82 is journaled in the uprights 11 and 90 which, together, support the top member 91 of the machine frame. The turret is rotated step by step by the action of the Geneva stop wheel 92 mounted on the 55 turret shaft 82.

The point cutting device, shown in Figs. 7 to 9, is supported in the housing 93 which at its ends has the bearing plates 94 carrying the cutter shaft 95. The shaft 95 has 60 the tool head 96 holding the cutter 97, angularly disposed with respect to the axis of the crayon acted on. The tool head 96 is provided with a dust shield 98 which throws the cut chips and dust into the chute 65 99 covered by the hood 100, pipes 101 lead-

ing them away from the machine. At the end opposite the tool head, the shaft 95 is splined to the sleeve 102 on which is mounted the drive pulley 103. Within the housing 93, on a ball bearing 104 attached to the 70 shaft 95, is mounted the collar 105 which is engaged by the fork 106, to move the shaft 95 back and forth toward and away from the crayon holding chucks in the turret. The fork 106 is mounted on the rod 107 75 slidably supported in the plates 94. On the rod 107 is fastened the adjusting block 108, adjusted by means of the screw 109, and connected by the rod 110 to the lever 111 which by its forward movement forces 80 the rod 107 with the fork 106 towards the turret and thus carries the shaft 95 with the tool head 96 and cutter 97 into position to cut the point on the crayon. After the crayon is pointed, the cutting head moves 85 back, and, at the next station of the turret, the pointed crayon is ejected.

The ejecting means is operated by the lever 112 which moves towards the turret and presses against the rods 87 of the chuck 90 then in discharging position. The bar 86 carried by these rods is thereby moved outwardly and pushes the crayon out of the chuck into the discharge chute 113 which is fastened to the side of the frame 10 by 95 means of the bracket 114.

The machine is driven by the motor 115 mounted on the frame 10 and carrying the pulley 116 which, through the belt 117, drives the pulley 118 containing within it the 100 clutch 119. The pulley 118 and clutch 119 are mounted on the shaft 120 supported by bearings in the frame 10. To the shaft 120 is keyed the pulley 121 driving, through the belt 122, the point cutting drive pulley 103. The shaft 120 also carries the pinion 123 meshing with the gear 124 mounted on the shaft 125 and driving the gear 126 which is keyed to the shaft 127 having the pinion 128. The latter pinion drives, through the gear 129, the cam shaft 130 on which are mounted the cams 131, 132, 133, 134, 135, and 136. The cam 131, through the roller 137, operates the lever 138 mounted on the shaft 139 in the bearing bracket 140. The lever 138, 110 through the connecting rod 42, is connected to the lever 41 which moves the label magazine up and down. The cam 132, through the roller 141, actuates the lever 56 fulcrumed on the shaft 142 in the bearing bracket 143, the said lever being connected by the rod 55 to the label carrier 46 and imparting to the latter its reciprocating motion. The cam 133, through the roller 144, operates the lever 145 which, through the rod 146, is 115 connected to the arm 147 mounted on the shaft 148 which also carries the lever 33 driving, through the link 32, the slide 24 of the crayon transfer. The lever 145 is 120 mounted on the shaft 149 supported by the 125

130

bearing brackets 150 and 151. The cam 134, through the roller 152, operates the lever 153, mounted on the shaft 149, which gives its up and down motion to the paste roller 57. 5 The cam 134, through the roller 154, furthermore operates the lever 155 which, through the rod 156, is connected to the lever 23 actuating the turret loading ram 75. The cam 135, through the roller 157, 10 operates the lever 158 which, through the rod 159, is connected to the lever 160 mounted on the shaft 161. On the shaft 161 is mounted the lever 164 which, through the rod 165, is connected with the lever 112 15 which actuates the push rods 87 of the turret when in their discharge position. The cam 135, through the roller 166, also operates the lever 167 which, through the rod 168, is connected with the lever 169 mounted on 20 the shaft 170. The lever 169 actuates the pointer clamp rod 171 which is guided in the bracket 163 and presses against the crayon while the latter is being pointed. The levers 158 and 167 are both mounted on the 25 shaft 150. The cam 136, through the roller 172, operates the lever 111 which gives its reciprocating motion to the point cutting mechanism.

The gear wheel 129, which drives the cam 30 shaft 130, meshes with the gear 173 mounted on the shaft 174 which is supported in a bearing of the upright 90. The shaft 174 carries an arm 175 having the roller 176 engaging the Geneva gear 92, moving the latter, and, through the shaft 82, the turret 81, one step for every revolution of the shaft 174. On the shaft 174 is mounted the bevel gear 177 meshing with the bevel 178 which is keyed to the shaft 69. The latter is 35 supported by the bearing bracket 179, and, through the sprocket gear 68 and chain 67, drives the sprocket wheel 66 which gives its motion to the paste drum 58.

The suction pump 52, mounted on the 40 frame 10 and connected by the hose 51 to the label carrier 46, is driven directly through the coupling 180 from the motor 115.

To start and stop the machine, the latter 45 is provided with a hand control lever 181 mounted on one end of the shaft 182, the other end of which, through the arm 183 and connecting rod 184, is connected with the clutch fork 185 which engages and disengages the clutch 119, the fork 185 being pivoted in the bracket 186 mounted on the frame 10.

What is claimed is:

1. The combination with label applying means, of crayon pointing means, ejecting means, and means whereby crayons are successively presented to said other means.
2. The combination with label applying means, of crayon pointing means, ejecting means, and means whereby crayons are suc-

cessively presented to said other means in the order herein specified.

3. The combination with label and crayon assembling means, of label applying means, crayon pointing means, ejecting means, and means whereby crayons are successively presented to said other means.

4. The combination with label and crayon assembling means, of label applying means, crayon pointing means, ejecting means, and means whereby crayons are successively presented to said other means in the order herein specified.

5. The combination with label applying means, of crayon pointing means, ejecting means, and means whereby crayons are successively presented to said other means, said pointing means including crayon holding means, crayon cutting means, and means for producing a relative approaching movement of said holding means and said cutting means to cause said cutting means to point a crayon in said holding means.

6. The combination with label applying means, of crayon pointing means, ejecting means, and means whereby crayons are successively presented to said other means, said pointing means including crayon holding means, crayon cutting means, and means for producing a relative approaching movement of said holding means and said cutting means in parallelism with the axis of a crayon in said holding means to cause said cutting means to point said crayon.

7. The combination with label applying means, of crayon pointing means, ejecting means, and means whereby crayons are successively presented to said other means, said pointing means including crayon holding means, crayon cutting means, and means for moving said cutting means toward said holding means to cause it to point a crayon in said holding means.

8. The combination with label applying means, of crayon pointing means, ejecting means, and means whereby crayons are successively presented to said other means, said pointing means including intermittently traveling crayon holding means, crayon cutting means, and means for producing a relative approaching movement of said holding means and said cutting means to cause said cutting means to point a crayon in said holding means while the latter is at rest.

9. The combination with label applying means, of crayon pointing means, ejecting means, and means whereby crayons are successively presented to said other means, said pointing means including an intermittently rotating turret having a series of crayon holding chucks, crayon cutting means for pointing a crayon in one of said chucks while said turret is at rest, and operating connections.

10. The combination with label applying

- means, of crayon pointing means, ejecting means, and means whereby crayons are successively presented to said other means, said pointing means including crayon holding means, a cutter angularly disposed with respect to the axis of a crayon in said holding means, and means for moving said cutter toward said holding means and about said axis to cause it to point said crayon.
- 10 11. The combination with label applying means, of crayon pointing means, ejecting means, and means whereby crayons are successively presented to said other means, said pointing means including crayon holding means, a cutter, a shaft supporting said cutter, and means for moving said shaft along and about its own axis to cause said cutter to point a crayon in said holding means.
12. The combination with label applying means, of crayon pointing means, ejecting means, and means whereby crayons are successively presented to said other means, said pointing means including crayon holding means, a cutter, a shaft supporting said cutter, cam-actuated means for longitudinally moving said shaft, and a belt-driven pulley splined to and rotating said shaft, whereby said cutter is caused to point a crayon in said holding means.
13. The combination with label applying means, of crayon pointing means, ejecting means, and means whereby crayons are successively presented to said other means, said ejecting means including parts associated with said pointing means, and extraneous means for intermittently operating said parts.
14. The combination with label applying means, of crayon pointing means, ejecting means, and means whereby crayons are successively presented to said other means, said ejecting means including parts associated with said pointing means, and cam-actuated extraneous means for intermittently operating said parts.
15. The combination with label applying means, of crayon pointing means, ejecting means, and means whereby crayons are successively presented to said other means, said ejecting means including parts carried by said pointing means, and extraneous means for intermittently operating said parts.
16. The combination with label applying means, of crayon pointing means, ejecting means, and means whereby crayons are successively presented to said other means, said ejecting means including parts carried by said pointing means and having two operating rods, and extraneous means for intermittently operating said rods.
17. The combination with label applying means, of crayon pointing means, ejecting means, and means whereby crayons are successively presented to said other means, said ejecting means including a spring-restrained plunger carried by said pointing means and having two operating rods, and extraneous means for intermittently operating said rods.
18. The combination with label applying means, of crayon pointing means, ejecting means, and means whereby crayons are successively presented to said other means, said pointing means including an intermittently rotating turret having a series of crayon holding chucks, and said ejecting means including a corresponding series of parts carried by said turret and associated with said chucks, and extraneous means for intermittently operating said parts while said turret is at rest.
19. The combination with label applying means, of crayon pointing means, ejecting means, and means whereby crayons are successively presented to said other means, said pointing means including crayon holding means, and said applying means including means for making a label adhesive, and means for loading the adhesive label and a crayon together in said holding means.
20. The combination with label applying means, of crayon pointing means, ejecting means, and means whereby crayons are successively presented to said other means, said pointing means including crayon holding means, and said applying means including means for loading a label and a crayon together in said holding means.
21. The combination with label applying means, of crayon pointing means, ejecting means, and means whereby crayons are successively presented to said other means, said pointing means including crayon holding means and said applying means including means for loading a label and a crayon together in said holding means with the ends of the label upstanding, and means for folding said ends down on said crayon.
22. The combination with label applying means, of crayon pointing means, ejecting means, and means whereby crayons are successively presented to said other means, said pointing means including crayon holding means, and said applying means including means for loading a label and a crayon together in said holding means with the ends of the label upstanding, and two successively acting means for folding said ends down on said crayon.
23. The combination with label applying means, of crayon pointing means, ejecting means, and means whereby crayons are successively presented to said other means, said pointing means including operating connections and an intermittently rotating turret having a series of crayon holding chucks, and said applying means including means for loading labels and crayons together in said chucks with the ends of the labels upstanding, movable means for folding the rear end of each label down on its crayon, and

stationary means adjacent the path of said chucks for folding the leading end of each label down on its crayon.

24. The combination with label applying means, of crayon pointing means, ejecting means, and means whereby crayons are successively presented to said other means, said pointing means including operating connections and an intermittently rotating turret having a series of crayon holding chucks, and said applying means including means for loading labels and crayons together in said chucks with the ends of the labels upstanding, a reciprocating folder for folding the rear end of each label down on its crayon, and a stationary brush adjacent the path of said chucks for folding the leading end of each label down on the crayon.

25. The combination with label and crayon assembling means, of label applying means, crayon pointing means, ejecting means, and means whereby crayons are successively presented to said other means, said pointing means including crayon holding means, and said assembling means including means for moving a label into position over said holding means, means for moving a crayon into position over the label so positioned, and means for loading said label and said crayon together into said holding means.

26. The combination with label and crayon assembling means, of label applying means, crayon pointing means, ejecting means, and means whereby crayons are successively presented to said other means, said pointing means including crayon holding means, and said assembling means including a label magazine, means for moving a label from said magazine into position over said holding means, means for making said label adhesive in transit, means for moving a crayon into position over the label so positioned, and means for loading said label and said crayon together into said holding means.

27. The combination with label and crayon assembling means, of label applying means, crayon pointing means, ejecting means, and means whereby crayons are successively presented to said other means, said pointing means including crayon holding

means, and said assembling means including means for moving a label into position over said holding means, a crayon hopper, means for moving a crayon from said hopper into position over the label so positioned, and means for loading said label and said crayon together into said holding means.

28. The combination with label and crayon assembling means, of label applying means, crayon pointing means, ejecting means, and means whereby crayons are successively presented to said other means, said pointing means including crayon holding means, and said assembling means including a label magazine, means for moving a label from said magazine into position over said holding means, means for making the label adhesive in transit, a crayon hopper, means for moving a crayon from said hopper into position over the label so positioned, and means for loading said label and said crayon together into said holding means.

29. The combination with label and crayon assembling means, of label applying means, crayon pointing means, ejecting means, and means whereby crayons are successively presented to said other means, said pointing means including crayon holding means, and said assembling means including means for moving a label into position over said holding means, means for moving a crayon into position over the label so positioned, and a cam-actuated plunger for loading said label and said crayon together into said holding means.

30. The combination with label and crayon assembling means, of label applying means, crayon pointing means, ejecting means, and means whereby crayons are successively presented to said other means, said pointing means including crayon holding means, and said assembling means including a cam-actuated slide for moving a label into position over said holding means, a cam-actuated slide for moving a crayon into position over the label so positioned, and a cam-actuated plunger for loading said label and said crayon together into said holding means.

In testimony whereof, I have signed my name to this specification.

CARL W. JOHNSON.
